UNITED STATES PATENT OFFICE.

JOSEPH NEEDHAM, OF NEW YORK, N. Y.

SOLDERING-IRON HEATER.

1,397,178.

Specification of Letters Patent.

Patented Nov. 15, 1921.

Application filed June 9, 1920. Serial No. 387,604.

To all whom it may concern:

Be it known that I, JOSEPH NEEDHAM, a citizen of the United States, and residing at New York, in the county of New York and State of New York, have invented certain new and useful Improvements in Soldering-Iron Heaters, of which the following is a specification, such as will enable those skilled in the art to which it appertains to

make and use the same.

This invention relates to soldering iron heaters and particularly to apparatus of this class designed to be used in workshops or other manufacturing institutions, and the object of the invention is to provide a heater of the class and for the purpose specified in which high pressure fuel gas is preferably employed as the heating medium; a further object thereof being to so construct the heating apparatus as to maintain an even degree of heat and to equally distribute the flame discharged into the heater; and with these and other objects in view the invention consists in an apparatus of the class and for the purpose specified which is simple in construction and operation and efficient in use.

The invention is fully disclosed in the following specification, of which the accompanying drawing forms a part, in which the separate parts of my improvement are designated by suitable reference characters in each of the views, and in which:—

Figure 1 is a front view of my improved heater;

Fig. 2 a partial section on the line 2—2 of Fig. 1;

Fig. 3 a partial section on the line 3—3 of Fig. 2; and,

Fig. 4 a partial section on the line 4—4 of Fig. 1 and indicating the method of supporting soldering irons in connection with the heater.

In the practice of my invention I provide a base frame 5, which is approximately rectangular in form and is provided in its corner portions with angle iron legs 6. The inner face of the frame 5 is provided below the top portion thereof with inwardly directed flanges 7 which form a table or support for a heater or furnace body 8 composed of separate top and bottom parts 9 and 10 joined, as shown at 11.

My improved heater is of the general form and construction of a furnace constructed on a comparatively small scale and

the separate parts 9 and 10 are preferably composed of fire-brick or similar material. The separate parts of the body 8 are molded separately to form when said parts are placed together, in the manner shown in the accompanying drawing, a central heating or furnace chamber 12 which opens outwardly through the front wall of the body 8 as shown at 13, and this chamber or the top and bottom walls thereof are provided with inwardly directed and longitudinally arranged beaded portions 14 and 15, which divide the chamber 12 into two longitudinally arranged and approximately cylindrical compartments 16 and 17 placed in communication as shown at 18.

The bottom part 10 of the body 8 is provided centrally of the chamber 12 with a passage 19 which opens into the chamber 12, as clearly shown in Figs. 2, 3 and 4, and mounted in the passage 19 is a gas burner with which is connected a supply pipe 21 which passes through one of the walls of the frame 5 and to which is secured a suitable injector 22, part of which is illustrated in Fig. 1.

Formed in the part 10 of the body 8 are oppositely directed passages 23 and 24, which communicate with the separate compartments 16 and 17, and also with passages 25 and 26 formed in the periphery of the parts 9 and 10 of the body 8, as clearly shown in Figs. 3 and 4. The passages 25 and 26 meet centrally of the top portion of the part 9 of the body 8 and communicate with a backwardly directed passage 27 formed in said part 9.

The body 8, or the separate parts 9 and 10 thereof, is inclosed in a suitable casing 28 provided on its inner face with a non-heat conducting facing 29, preferably composed of asbestos. The casing 28 is held in position by front and back approximately arc-shaped bands 30 and 31 into which the front and back edge portions of the casing 28 fit, as clearly shown in Figs. 2 and 4. The bands 30 and 31 pass into the top portion of the frame 5 and are secured thereto by screws 32 which securely hold the casing 28 in position. The bands 30 and 31 are each composed of L-shaped or approximately L-shaped strips, and one of the flanges at the top of the strips 31 is enlarged as shown at 33 in Fig. 2 sufficiently to cover the rear end portion of the passage 27. The band 31 is also provided centrally of the top portion

thereof with an upwardly directed tubular extension 34 which is approximately elliptical in form and a flue pipe may, if desired, be connected with said tubular extension to 5 carry the gases of combustion to a suitable point at which they may be discharged. The casing 28 and facing 29 thereof are also apertured as shown at 35 in line with the tubular extension 34 in order to place the 10 passage 27 in communication therewith.

The front of the frame 5 is provided with an approximately L-shaped extension 36, and the upwardly directed portion 37, or the top face thereof, is notched out as shown at 38. 15 In the use of the apparatus and when suitable soldering irons 39, two of which are indicated in dotted lines in Fig. 4, are placed in the heater, or the chamber 12 thereof, the shanks 40 of said soldering irons will rest 20 in the notched portion 38 of the extension 36.

The part 10 of the body 8 is recessed at the opposite sides of the central bead 15 thereof, and at the opposite sides of the central transverse plane of the chamber 12, as shown at 25 41 and 42. The recesses 41 are in the compartment 16, while the recesses 42 are in the compartment 17, and these recesses form in the compartments 16 and 17 central ribs 43 and 44 respectively. The ribs 43 and 44 30 form the supports for the head end portions 45 of the soldering irons indicated in dotted lines in Fig. 4, and the recesses 41 and 42 at the opposite sides of said ribs permit of the passage of the flame or products of combustion 35 around the head portions 45 to thoroughly and evenly heat said head portions.

In the use of the device the gaseous mixture is introduced into the injector 22 through the pipe 21 to the burner 20 and is 40 ignited within the chamber 12 and the flame from the burner 20 strikes the central beaded portion 14 of the chamber 12 and directs the flame laterally as indicated by the arrows in Fig. 3, and the products of combustion are 45 discharged laterally through the passages 23 and 24 in the part 10 of the body 8 upwardly through the passages 25 and 26 into the passage 27 at the top of the part 9 and out through the tubular extension 34. It 50 will also be apparent that the flame within the separate compartments 16 and 17 will pass through the recessed portions 41 and 42 around the head portions 45 of the soldering iron to heat the same.

55 By passing the products of combustion over the part 9 of the furnace body 8, I prevent the chilling of said furnace body and keep said furnace body at an even temperature at all times. The passages 25, 26 and 27 60 as well as the passages 23 and 24 function as a jacket for the central portion of the furnace body 8 for the chamber 12 of said body.

It will be apparent that soldering irons 65 may be placed in and removed from the separate compartments 16 and 17 whenever de-

sired, and with my improved construction the head portions 45 of the soldering irons will be equally and properly heated by reason of the method of distributing the flame and the products of combustion around said 70 head portions. It will also be apparent that while I have described my improved heater or furnace, as particularly designed for the purpose of heating soldering irons, I am not necessarily limited in this respect as the apparatus 75 may be used for heating various other articles, if desired, and changes in and modifications of the details of construction herein shown and described may be made, within the scope of the appended claims, 80 without departing from the spirit of my invention or sacrificing its advantages.

Having fully described my invention, what I claim as new and desire to secure by Letters Patent, is:—

85 1. A heater of the class described comprising a furnace body provided with an approximately central chamber which opens outwardly through said furnace body, said chamber being composed of two approximately cylindrical chambers having laterally directed passages in communication therewith, the periphery of said furnace body being provided with upwardly and inwardly directed passages in communication with 90 said laterally directed passages, the top of said furnace body being provided with a backwardly directed passage in communication with said upwardly and inwardly directed passages, said body being provided centrally of the chamber therein with a downwardly directed passage, and a burner 95 device mounted in said last named passage.

100 2. A heater of the class described comprising a furnace body provided with an approximately central chamber which opens outwardly through said furnace body, said chamber being composed of two approximately cylindrical chambers having laterally directed passages in communication therewith, the periphery of said furnace body being provided with upwardly and inwardly directed passages in communication with 105 said laterally directed passages, the top of said furnace body being provided with a backwardly directed passage in communication with said upwardly and inwardly directed passages, said body being provided centrally of the chamber therein with a downwardly directed passage, a burner device 110 mounted in said last named passage, and means in the chamber of said body for directing the flame and products of combustion from said burner laterally into the separate compartments of said chamber and out 115 through the laterally directed passages and thus through said upwardly, inwardly and backwardly directed passages.

120 3. A heater of the class described comprising a furnace body provided with an ap- 125

- proximately central chamber which opens outwardly through said furnace body, said chamber being composed of two approxi-
5 mately cylindrical chambers having later-
ally directed passages in communication therewith, the periphery of said furnace body being provided with upwardly and in-
wardly directed passages in communication with said laterally directed passages, the top
10 of said furnace body being provided with a backwardly directed passage in communication with said upwardly and inwardly directed passages, said body being provided centrally of the chamber therein with a
15 downwardly directed passage, a burner device mounted in said last named passage, and said furnace body being provided with ribs arranged centrally and transversely of the compartments at the opposite sides of which
20 are formed recesses in the separate compartments.
4. A soldering iron heater of the class described comprising a suitable frame, a furnace body mounted in the frame, said body
25 being provided with a plurality of approxi- mately cylindrical compartments which open outwardly therethrough, laterally directed passages formed in said body and in communication with said compartments, the per-
30 phery of said body being provided with upwardly and inwardly directed passages in communication with said first named pas-
35 sages and with a backwardly directed pas-
40 sage in communication with said last named passages, a casing inclosing the periphery of said furnace body and provided with a flue discharge in communication with said last named passage, said furnace body being provided with a downwardly directed pas-
45 sage formed centrally of the separate compartments and in communication therewith, and a burner device mounted in said last named passage.
5. A soldering iron heater of the class de-
50 scribed comprising a suitable frame, a furnace body mounted in the frame, said body being provided with a plurality of approxi- mately cylindrical compartments which open outwardly therethrough, laterally directed
55 passages formed in said body and in communication with said first named pas-
60 sages and with a backwardly directed pas-
65 sage in communication with said last named passage, a casing inclosing the periphery of said furnace body and provided with a flue discharge in communication with said last named passage, said furnace body being pro-
vided with a downwardly directed passage formed centrally of the separate compartments and in communication therewith, a burner device mounted in said last named
70 passage, and the furnace body being pro-

vided within the compartments therein with recesses which form ribs therebetween and within the separate compartments centrally thereof.

6. A soldering iron heater of the class de-
70 scribed comprising a suitable frame, a furnace body mounted in the frame, said body being provided with a plurality of approxi- mately cylindrical compartments which open outwardly therethrough, laterally directed
75 passages formed in said body and in communication with said compartments, the periphery of said body being provided with upwardly and inwardly directed passages in communication with said first named pas-
80 sages and with a backwardly directed pas-
85 sage in communication with said last named passages, a casing inclosing the periphery of said furnace body and provided with a flue discharge in communication with said last named passage, said furnace body being pro-
90 vided with a downwardly directed passage formed centrally of the separate compartments and in communication therewith, a burner device mounted in said last named
95 passage, the furnace body being provided within the compartments therein with re-
cesses which form ribs therebetween and within the separate compartments centrally thereof, and said frame being provided at
100 one side thereof with an L-shaped extension which forms a support for the shank por-
tions of said soldering irons when placed in the separate compartments of the furnace body.

7. A heater of the class described compris-
105 ing a frame, a furnace body mounted in said frame to form a chamber at the sides and top portion of said body, said body being provided with a combustion chamber which opens outwardly through one end of said body, a burner device in communication with said combustion chamber and means for discharging products of combustion through the furnace body at the opposite
110 sides of said combustion chamber, and upwardly through said first named chamber.

8. A heater of the class described compris-
115 ing a frame, a furnace body mounted in said frame to form a chamber at the sides and top portion of said body, said body being provided with a combustion chamber which opens outwardly through one end of said body, a burner device in communication with said combustion chamber and means for dis-
120 charging products of combustion through the furnace body at the opposite sides of said combustion chamber, and means at one end portion of said frame for discharging the products of combustion from said first
125 named chamber.

9. A heater of the class described compris-
130 ing a frame, a furnace body mounted in said frame to form between the same and said frame at the opposite sides and top of said

body a discharge passage, said body being provided with a chamber which opens outwardly through one end thereof, said chamber being divided into two approximately cylindrical compartments, a burner device mounted in said body and communicating with said chamber and compartments centrally thereof, said body being provided with laterally directed passages in communication with the separate compartments and said discharge passage, the products of combustion being adapted to pass upwardly into the separate compartments of said chamber, downwardly and outwardly through said laterally directed passages, and upwardly through said discharge passage, and means for discharging said products of combustion from one end portion of said frame.

20 10. A heater of the class described comprising a frame, a furnace body mounted in said frame and composed of separate detachably connected parts, two of said parts being recessed centrally on abutting faces

thereof to form in said body and between 25 said parts two approximately cylindrical compartments which form the combustion chamber of the heater, one of the separate parts of said body being provided with laterally directed passages in communication 30 with the separate compartments of said body and with discharge passages at opposite sides of said body, said discharge passages communicating with each other at the top of said body, and one of the separate parts 35 of the furnace body being provided with an aperture in communication with said combustion chamber and in which a burner device is adapted to be mounted.

In testimony that I claim the foregoing 40 as my invention I have signed my name in presence of the subscribing witnesses this 8th day of June, 1920.

JOSEPH NEEDHAM.
